US0D1002376S

(12) **United States Design Patent** (10) Patent No.: **US D1,002,376 S**
(45) Date of Patent: ** Oct. 24, 2023

(54) **CONTAINER**

(71) Applicant: **Altium Packaging LP**, Atlanta, GA
(US)

(72) Inventors: **Grover John Manderfield, Jr.**,
Marietta, GA (US); **Joey Arlin Palmer**,
Atlanta, GA (US)

(73) Assignee: **Altium Packaging LP**, Atlanta, GA
(US)

(**) Term: **15 Years**

(21) Appl. No.: **29/725,092**

(22) Filed: **Feb. 21, 2020**

(51) LOC (14) Cl. **09-01**

(52) U.S. Cl.

USPC **D9/569**; D9/535

(58) **Field of Classification Search**

(57) **CLAIM**

The ornamental design for a container, as shown and described.

DESCRIPTION

FIG. 1 is a perspective view of a container showing the claimed design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the figures illustrate the portions of the container and form no part of the claimed design.

1 Claim, 7 Drawing Sheets
